UNITED STATES PATENT OFFICE

171,234

POP-UP FIGURE TOY

Makoto Sugita, Itchikawa City, Japan, assignor
to Ross Products, New York, N. Y.

Application October 1, 1953, Serial No. 27,039

Term of patent 14 years

(Cl. D34—15)

To all whom it may concern:

Be it known that I, Makoto Sugita, a citizen of Japan, residing at 286-5 Chome Slugano-Machi, Itchikawa City, Chiba Prefecture, Japan, have invented a new, original, and ornamental Design for a Pop-Up Figure Toy, of which the following is a specification, reference being had to the accompanying drawing, forming a part hereof.

Fig. 1 is a top perspective view of the pop-up figure toy showing my new design as it appears in deflated position.

Fig. 2 is a top perspective view of the pop-up figure toy showing my new design as it appears in inflated position.

The characteristic features of my new design are shown in solid lines.

I claim:

The ornamental design for a pop-up figure toy, as shown and described.

MAKOTO SUGITA.
